(57) **CLAIM**

The ornamental design for a HDMI splitter, as shown and described.

DESCRIPTION

FIG. 1 is a rear, left and top perspective view of a HDMI splitter showing my new design;

FIG. 2 is a front, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view thereof, illustrated in a second position of FIG. 2.

The broken lines in the figures illustrate portions of the HDMI splitter that form no part of the claimed design.

1 Claim, 9 Drawing Sheets
